UNITED STATES PATENT OFFICE.

VICTOR M. LOKER, OF TRACY, CALIFORNIA.

RAIL-EXPANSION ADJUSTER.

Application filed February 11, 1925. Serial No. 8,406.

To all whom it may concern:

Be it known that I, VICTOR M. LOKER, a citizen of the United States of America, residing at Tracy, county of San Joaquin, 5 State of California, have invented certain new and useful Improvements in Rail-Expansion Adjusters; and I do declare the following to be a full, clear, and exact description of the same, reference being had 10 to the accompanying drawings, and to the characters of reference marked thereon, which form a part of this application.

This invention relates to railway maintenance of way equipment, and particularly 15 to a device to be used in maintaining the rails in proper spaced relation to each other at their ends.

As all maintenance of way workers know, rails have a habit of creeping one way or 20 the other with the expansion by heat or with the gradual movement imparted thereto by trains moving thereover. Often therefore the rails must be pushed one way or the other to equalize the spaces between 25 the ends of the different rails. The rails must also be spread at times to enable the insulating members necessary in connection with signaling systems to be placed therebetween.

Up to the present time as far as I am aware, the only means available for spreading the rails is a wedge driven between the 30 rail ends by a sledge hammer. Very frequently there is not sufficient space between 35 the ends to start the wedge and the rails must be forcibly shifted in some other and even more crude way by a gang of section hands.

The principal object of my invention 40 therefore is to provide a device, which may be readily installed and operated by one man by means of which the rails may easily and quickly be either drawn together or moved apart a desired distance, no matter 45 how close together or how far apart they may be at the start.

I have also arranged the device so that light or heavy rails may be worked on with the one tool.

A further object of the invention is to 50 produce a simple and inexpensive device and yet one which will be exceedingly effective for the purpose for which it is designed.

These objects I accomplish by means of 55 such structure and relative arrangement of

parts as will fully appear by a perusal of the following specification and claims.

In the drawings similar characters of reference indicate corresponding parts in the several views:

Fig. 1 is a top plan view of the implement as applied to the rails, one rail being partly cut away.

Fig. 2 is an end elevation of the device as in position for operation.

Referring now more particularly to the characters of reference on the drawings the numeral 1 denotes a pair of symmetrical and similar blocks arranged in continuous but separated alinement. These blocks 70 could be solid but are cut away intermediate their ends to lighten the same.

A heavy rod or shaft 2 projects lengthwise through both blocks, said shaft being threaded right hand in one block and left 75 hand in the other, as shown at 3 and 4 respectively.

Formed with the blocks along both sides thereof are plates 5 adapted to abut against the web 6 of the rails between the head 7 80 and base flange 8 thereof.

Projecting from the plates 5 at right angles thereto are stub pins 9, those on each block being spaced apart a length so that they will fit in the holes 10 commonly provided in the webs of the rails for the fish plate bolts:

The pins 9 on each side of the blocks are of different sizes so as to fit holes 10 of different weights of rails, such holes being 90 smaller in the lighter rails than in the heavier ones.

One end of the shaft 2 is squared off as at 11 so that a lever 12 having a similarly shaped orifice at one end may be removably applied to the shaft to turn the same.

In placing the device on the rails the fish plates at the rail ends to which the implement is to be applied are removed, and the spikes of the end plates at the other ends 100 of the rails are removed. The blocks 1 are then separated the necessary distance so that the pins 9 therein are in alinement with the two sets of holes 10 in the two rail ends. The blocks are then placed so that the plates 5 abut against the rail webs with the pins 9 projecting through the holes 10. A plate 13 having longitudinal slots 14, one for each pin 9, is then placed over the pins against the opposite face of the webs. Washer 110

plates 15, one for both pins of each block, are then placed over the respective pairs of pins outwardly of the plate 13. Drift keys 16 are then driven through transverse slots 5 17 cut in the pins 9 so as to maintain the plates 5, webs 6, and plates 13 and 15 in close relationship.

The lever 12 is then applied to the shaft 2 and it will be evident that depending on 10 which way it is turned the block and consequently the rails will be moved one way or the other.

The device is so designed that except for 15 the lever which can be easily and instantly removed when necessary, no part projects above the rail level or alongside the rail heads.

There is therefore no interference with 20 the passage of a train over the track while the device is still applied thereto.

When the rails are expanded or drawn together the necessary distance the appliance is of course removed and the fish plates coupled to the rails again.

25 From the foregoing description it will be readily seen that I have produced such a device as substantially fulfills the objects of the invention as set forth herein.

While this specification sets forth in detail 30 the present and preferred construction of the device, still in practice such deviations from such detail may be resorted to as do not form a departure from the spirit of the invention, as defined by the appended 35 claims.

Having thus described my invention what I claim as new and useful and desire to secure by Letters Patent is:

40 1. A rail spacing adjuster comprising a pair of aligned and separated members both sides of which are adapted to abut against

the webs of rails at adjacent ends thereof, means mounted in connection with said members for moving them to and from each other, and pins projecting laterally from both sides of said members and adapted to pass through the fish-plate bolt-holes in the rails.

2. A rail spacing adjuster comprising a pair of aligned and separated members both 45 sides of which are adapted to abut against the webs of rails at adjacent ends thereof, means mounted in connection with said members for moving them to and from each other, and pins permanently mounted on 50 and projecting laterally from both sides of said members and adapted to pass through the fish-plate bolt-holes in the rails, the pins on one side being a different size from those on the other whereby to enable the device 55 to be applied without change, to rails having 60 different sizes of bolt-holes.

3. A rail spacing adjuster comprising a pair of aligned and separated members adapted 65 to abut against the webs of rails at adjacent ends thereof, pins projecting laterally from said members and adapted to pass through the fish-plate bolt-holes in the rails, means applied to said members for moving the same to and from each other, a plate 70 having longitudinal slots to pass over the pins of both members from the side of the rail opposite to said members, a single washer-plate for the pins of each member adapted to be placed over the pins outwardly of the slotted plate, the pins having 75 transverse slots extending beyond the washer plates, and taper drifts passable through said pin slots.

In testimony whereof I affix my signature.

VICTOR M. LOKER.
